UNITED STATES PATENT OFFICE

FRANKLIN JUDGE, OF GREENFIELD, MASSACHUSETTS, ASSIGNOR TO GREENFIELD TAP & DIE CORPORATION, OF GREENFIELD, MASSACHUSETTS, A CORPORATION OF MASSACHUSETTS

DIE STOCK

Application filed November 2, 1929. Serial No. 404,420.

This invention relates to a die stock of the type used for holding thread cutting dies.

It is the object of my invention to provide new and improved means for adjusting the 5 cutters in a die stock so that a thread of the desired diameter may be produced.

A further object is to provide improved means for centering the work in a die stock while the thread is being started.

10 My invention further relates to arrangements and combinations of parts which will be hereinafter described and more particularly pointed out in the appended claims.

A preferred form of the invention is shown 15 in the drawings in which

Fig. 1 is a plan view of my improved die stock;

Fig. 2 is a side elevation thereof, looking in the direction of the arrow 2 in Fig. 1;

20 Fig. 3 is a sectional side elevation, taken along the line 3—3 in Fig. 1;

Fig. 4 is a plan view of the die stock with the cover plate removed;

Fig. 5 is a plan view of the casing, showing 25 certain cam surfaces;

Fig. 6 is a plan view of the cutter support;

Fig. 7 is a partial side elevation thereof, looking in the direction of the arrow 7 in Fig. 6; and

30 Fig. 8 is a bottom view of the die stock showing the means for supporting the work.

Referring to the drawings, my improved die stock comprises a casing 10 having opposite projecting portions 12 in which handle rods 13 are secured. The casing 10 is provided with a series of inner cam surfaces 14 and is threaded to receive adjusting screws 15 and 16, all for purposes to be described.

35 A disc-like cutter support 20 is mounted 40 for limited angular movement in the casing 10 and is provided with a plurality of spaced guideways 22 adapted to receive cutters 24. These cutters 24 are freely slidable in the guideways 22 but are yieldingly engaged by 45 spring-pressed balls 26 at the sides thereof, which act to retain the cutters 24 from accidental displacement when the support 20 is removed from the casing 10.

The support 20 is provided with spaced 50 shoulders 28 positioned for engagement by

the inner ends of the adjusting screws 15 and 16. The outer ends of the cutters 24 are shaped to correspond to the cam surfaces 14 which they directly engage.

A cover plate 30 is secured to the support 55 20 and prevents outward displacement of the cutters 24. The cover plate 30 projects beyond the cylindrical outer face of the support 20 and is engaged by clamping collars or washers 32 secured to the casing 10 by screws 60 33. The collars 32 are slotted off at one side, as indicated at 34, so that the cover plate and cutter support together with the cutters may be removed as a unit by turning the washers 32 angularly, but without entirely removing 65 the same from the casing 10.

With this construction, it will be seen that the cutters 24 are each firmly seated against one of the cam surfaces 14 and that by loosening the adjusting screw 16 and tightening 70 the screw 15, the cutters may be simultaneously and equally forced inward to decrease the size of the thread to be cut. The reverse operation will permit the cutters to be forced outward, causing an increase in the thread 75 diameter.

The cover plate 30 may be provided with an index line 40 (Fig. 1) co-operating with a corresponding index line 42 on the casing 10, so that the direction and amount of adjustment may be visibly indicated.

A disc or bottom plate 50 is placed into the cylindrical opening of the casing 10 and is held from rotation therein by a pin 51 (Fig. 8). A plurality of work-engaging fingers 52 85 are pivoted at 53 to the plate 50 and are provided with pins 54 projecting outward into cam slots 55 formed in a flanged cap or cover 56. The flanged portion 57 of the cover 56 is centered in an annular recess 58 of the plate 90 50. The portion 57 is also provided with an annular groove 60 to receive the concave edge portions of clamping plates 62, secured by clamping screws 63.

When the screws 63 are loosened, the 95 flanged cover plate 56 may be turned angularly to adjust the fingers 52 to the diameter of the work to be engaged thereby. The parts are then secured in the desired position by tightening the screw 63.

I have thus provided a die stock in which the cutters may be readily adjusted to take up wear or to provide a desired oversize or undersize thread.

5 I have also provided improved and effective means for centering the work in the die stock while the thread is being started. All parts are of simple and effective construction, easily manufactured and not liable to 10 injury or breakage when in use.

Having thus described my invention and the advantages thereof, I do not wish to be limited to the details herein disclosed, otherwise than as set forth in the claims, but what 15 I claim is:

1. A thread cutting mechanism comprising a casing, a cutter support mounted for a limited angular adjustment in said casing and comprising a body member having 20 guideways therein and a plate rigidly connected thereto adjacent said guideways, a plurality of cutters slidably mounted in said guideways and retained therein by said plate, said body member, cutters and plate being 25 removable from the casing as a unit, means to adjust said support angularly, and cam means effective to slide each cutter inward as said support is adjusted angularly in said casing.

30 2. A thread cutting mechanism comprising a casing, a cutter support mounted for a limited angular adjustment in said casing and comprising a body member having guideways therein and a plate rigidly connected 35 thereto adjacent said guideways, a plurality of cutters slidably mounted in said guideways and retained therein by said plate, said body member, cutters and plate being removable from the casing as a unit, means to adjust 40 said support angularly, cam means effective to slide each cutter inward as said support is adjusted angularly in said casing, and means to retain said support in position in the casing including a rotatable washer having a slabbed-off side.

45 3. A thread cutting mechanism comprising a casing, a cutter support mounted for a limited angular adjustment in said casing and comprising a body member having guideways 50 therein and a plate rigidly connected thereto adjacent said guideways, a plurality of cutters slidably mounted in said guideways and retained therein by said plate, said body member, cutters and plate being removable 55 from the casing as a unit, and means to adjust said support angularly, said casing having cam surfaces formed thereon and positioned to engage the outer ends of said cutters and effective to slide each cutter inward as 60 said support is adjusted angularly in said casing.

In testimony whereof I have hereunto affixed my signature.

FRANKLIN JUDGE.
